(57) **CLAIM**

The ornamental design for a watch display case, as shown and described.

DESCRIPTION

FIG. 1 is a front, top, and left perspective view of a watch display case, in an open configuration showing our new design;

FIG. 2 is a front, top, and left perspective view of the watch display case, in a closed configuration showing our new design;

FIG. 3 is a front elevational view thereof;

FIG. 4 is a rear elevational view thereof;

FIG. 5 is a left side elevational view thereof;

FIG. 6 is a right side elevational view thereof; and,

FIG. 7 is a top plan view thereof.

The broken line showing of the inside of the drawer is for the purpose of illustrating portions of the watch display case that form no part of the claimed design.
